UNITED STATES PATENT OFFICE

GEORGE D. McCABE, OF CHICAGO, ILLINOIS

ELEMENT SUPPORTING STEM CONSTRUCTION

Application filed October 31, 1930. Serial No. 492,447.

This invention relates to an element supporting stem construction, and an object of the invention is the provision of an improved construction of this character particularly adapted for supporting elements in tubes, such as radio vacuum tubes, although it is to be understood that the invention is not necessarily confined to this particular use. A more specific object resides in the provision of a tube stem designed and arranged to maintain the element supporting members in a relationship whereby increased support for the elements is afforded and bending or distortion of the supports prevented. The construction of the present invention may be applied to advantage in tubes such as gaseous rectifiers, photo-electric cells, ultra-violet ray lamps, incandescent lamps, mercury vapor lamps, mercury switches, X-ray tubes, gaseous illuminating signs, etc. In radio tube construction, for example, the element supporting members such as the wires which support the plate and grid elements, are generally constructed of soft metal, such as soft nickel wire, and any sudden jarring, such as frequently occurs in transportation and handling, has a tendency to cause a bending or distortion of the wire supports. Such bending or distortion is frequently the cause of microphonics or other impairment in the efficiency of the tube. A more particular object of the invention, therefore, is the provision of a supporting stem in which the wires are disposed in a plurality of vertical planes whereby increased stability is provided by reason of lateral supports arranged to reinforce the element supporting members.

Other objects will appear hereinafter.

The invention consists in the combinations and arrangements of parts hereinafter described and claimed.

The invention will be best understood by reference to the accompanying drawing forming a part of this specification, and in which:

Fig. 1 is an elevational view, partly broken away, of a radio tube embodying the present invention;

Fig. 2 is an enlarged perspective view of the structure shown in Fig. 1, with the en-

closing tube partly broken away and the plate omitted to more clearly illustrate the construction;

Fig. 3 is a plan view of the element supporting members shown in Fig. 2; and

Fig. 4 is an inverted sectional view taken substantially on the line 4—4 of Fig. 2, with the plate element in position.

As illustrated in the drawing, the invention is shown incorporated in a radio vacuum tube having an enclosing glass shell or tube 6, base 7, and contact prongs 8. The preferred embodiment of the present invention comprises an element supporting stem 9 which is suitably secured in the base 7 for the purpose of supporting the various elements that may be employed. Stem 9 is preferably formed of glass which is compressed or molded into the outline or formation shown after positioning of the element supporting members or wires. This distinctive formation comprises a vertical central supporting portion 10, at one end of which is provided a vertically transverse supporting portion 11 and at the opposite end a second vertically transverse supporting portion 12. In the formation of the stem a plurality of element supporting members are sealed within the central portion 10, and in the embodiment shown these members take the form of wires 13, 14, 15, 16, and 17. These wires may be composed of any suitable material such as soft nickel, and, as shown, are disposed in, or substantially in the same vertical plane, and for convenient reference may be termed the main supporting members or wires. The wires 13 to 17, inclusive, may extend any desired distance within the stem 9, and a preferred construction is to have these wires embedded but a short distance and the connections continued by copper clad wire. These main supporting wires are supplemented by a plurality or set of auxiliary supporting wires 18 and 19, mounted in the transverse end portion 11 and disposed in or substantially in a vertical plane perpendicular to the plane of the main supporting wires 13 and 17. A second set or plurality of auxiliary supporting wires 20 and 21 are disposed in the opposite transverse end portion

12 and are thus likewise disposed in a vertical plane substantially perpendicular to the plane of the main wires 13 and 17, and in the construction shown, parallel to the plane of 5 supports 18 and 19. Wires 18, 19, 20, and 21 may be embedded within the glass stem 9 any desired distance in order to afford a relatively rigid support above the stem, but in the preferred construction, inasmuch as 10 all or nearly all of these wires function as reinforcing members, they extend a greater distance downwardly than the main element supports 13 to 17.

It will be evident that any desired arrangement 15 of elements may be employed inasmuch as the supporting wires are disposed in a plurality of vertical planes, and may therefore be utilized to advantage not only directly to support the elements but to reinforce laterally both the elements and the element supports. For example, in the embodiment shown, wires 18 and 21 may be bent laterally and then upwardly, as shown, to provide vertical supports for a plate 22. Wires 13 and 20 25 17 may then be bent as shown, to provide upwardly extending portions disposed in the same transverse plane as the plate supporting portions of wires 18 and 21, and these upper portions of wires 13 and 17 may be 30 employed to support a grid 23 enclosed within plate 22. Similarly, wires 14 and 16 may be bent laterally and then turned upwardly to provide supports for filament 24. The central wire 15 may then be bent laterally 35 and upwardly to clear the plate 22, and provided at its upper extremity with a lateral anchoring wire 25 for supporting the upper portion of filament 24. Thus, in the construction shown, all of the wires, with the exception of the filament supporting wires 14 and 16, extend substantially to the same height and are interconnected by means of a plate of suitable dielectric material such as mica 26 which is suitably pierced to receive the upper extremities of the wires, after 40 which the ends of the wires may be enlarged by pressing to confine the mica plate 26. As shown, the mica plate 26 is preferably provided with a central opening for connecting the anchor wire 25 with the filament 24, and in lieu of enlargement of the ends of the respective wires by pressing, the mica 26 may be rigidly secured in place by means of small welded straps or equivalent means.

45 The structure entails no greater expense in manufacture, and the particular arrangement of the element supports, including the lateral reinforcing members, such as wires 19 and 20, in the illustrative embodiment, 50 increases the stability of the supports as a whole. Consequently, distortion of the elements or supports, such as frequently occurs in transportation and handling, is substantially prevented and durability and efficiency 55 of the tube increased.

While I have illustrated and described the preferred form of construction for carrying my invention into effect, this is capable of variation and modification without departing from the spirit of the invention. I, therefore, do not wish to be limited to the precise details of construction set forth, but desire to avail myself to such variations and modifications as come within the scope of the appended claims.

Having thus described my invention, what I claim as new and desire to secure by Letters Patent is:

1. A tube stem construction of the character described, comprising a main vertical 80 element supporting portion, a vertical transverse element supporting portion disposed transversely of said main portion at one end thereof, a plurality of main element supporting wires embedded in said main portion and disposed substantially in the same vertical plane, and a plurality of auxiliary element supporting wires embedded in said transverse portion and disposed in a vertical plane transversely of the vertical plane of said main element supporting wires.

2. A tube stem construction of the character described, comprising a main vertical element supporting portion, a vertical transverse element supporting portion disposed transversely of said main portion at one end thereof, a plurality of main element supporting wires embedded in said main portion and disposed substantially in the same vertical plane, a plurality of auxiliary element supporting wires embedded in said transverse portion and disposed in a vertical plane transversely of the vertical plane of said main element supporting wires, a second vertical transverse element supporting portion disposed transversely of said main portion at the opposite end thereof, and a plurality of auxiliary element supporting wires embedded in said second transverse portion and disposed in a vertical plane transversely of the vertical plane of said main element supporting wires.

In testimony whereof I have signed my name to this specification.

GEORGE D. McCABE.
